SLIPPER

Donna L. Fenlason, New York, N. Y.

Application December 15, 1954, Serial No. 33,566

Term of patent 14 years

(Cl. D7—7)

To all whom it may concern:

Be it known that I, Donna L. Fenlason, have invented a new, original, and ornamental Design for a Slipper, of which the following is a specification, reference being had to the accompanying drawing, forming a part hereof.

Fig. 1 is a side view of a slipper in accordance with the invention;

Fig. 2 is a top view of the slipper shown in Fig. 1; and

Fig. 3 is a top view of the slipper showing the ties in an extended position.

What is claimed is:

The ornamental design for a slipper, substantially as shown.
